UNITED STATES PATENT OFFICE.

WILLIAM M. GOLDSMITH, OF CINCINNATI, OHIO.

WALL OR PARTITION.

1,136,792.

Specification of Letters Patent. Patented Apr. 20, 1915.

Application filed October 7, 1912. Serial No. 724,284.

To all whom it may concern:

Be it known that I, WILLIAM M. GOLDSMITH, a citizen of the United States of America, and resident of Cincinnati, county 5 of Hamilton, and State of Ohio, have invented certain new and useful Improvements in Walls or Partitions, of which the following is a specification.

This invention relates to fire-proof partitions and has for an object to produce an improved form of partition or wall which may be quickly, easily, and cheaply erected and which may be manufactured at a low cost.

15 To these ends the invention consists in certain novel features of construction which are herein described and are illustrated in the drawings accompanying and forming a part of this application.

20 In the drawings Figure 1 is a fragmental horizontal sectional perspective view of a partition or wall embodying my invention. Fig. 2 is a fragmental horizontal sectional view, on an enlarged scale, of a modified 25 form of wall or partition which forms an embodiment of my invention. Fig. 3 is a fragmental horizontal sectional view of a wall, or partition, which also forms an embodiment of my invention.

30 The partitions or walls illustrated, as embodiments of my invention, are each composed of a plurality of metal sheets or construction members 3, which are uniform in shape and size and which may be prepared 35 to receive a coating of mortar, plastering or similar material, if desired.

The metal sheets or construction members 3 employed in the construction of the walls illustrated in Fig. 1 and Fig. 2 are of uniform 40 size and shape and each sheet has an L-shaped or angular partition-forming flange formed along one of its vertical edges. The longer leg 4 of the flange on each sheet extends at right angles to the sheet and the 45 shorter and outer leg or foot-flange 5 extends at right angles to the leg 4, is parallel to the sheet and is located on the same side of the leg 4 as the sheet.

The wall illustrated in Fig. 1 is composed 50 of two sets of overlapping sheets 3 arranged so that each sheet of each set over-laps the flanged end of an adjacent sheet, and the sheets are so located that their flanges project inwardly with relation to the other set 55 of sheets and contact with the other set. This forms a wall having vertical stiffening

members, located at intervals along its length. The spacing of the stiffening members or flanges of the wall is of course dependent upon the length of the sheets and 60 the amount they overlap each other when assembled in a wall.

The sheets of each set are located so that their flanged edges extend in the same direction and each sheet is overlapped by the 65 unflanged vertical edges of an adjacent sheet. Any suitable means may be employed for securing the sheets of each set together and for securing each sheet to the floor and ceiling structure of the building, in which 70 the wall or partition is located. If the sheets are formed of expanded metal or are perforated they may be easily joined or secured together by means of wires or flexible staples. The sheets of the two sets are so 75 spaced that the flanges of one set are located midway between the flanges of the other set and consequently aid in supporting the central portions of the sheets of the other set. If desired, the flanges of one set may be 80 secured to the sheets of the other by perforating the flanges and the sheet, and then lacing a wire or staple through the perforations, or they may be secured together by 85 any other suitable means.

In Fig. 2 a modified form of wall is shown, in which the flanges of the sheets forming one side of the wall interlock with the flanges of the sheets forming the other side, and therefore produce stiffening ribs 90 or supports of twice the strength and rigidity of those shown in Fig. 1. The unflanged vertical edges of the sheets overlap the flanged edges in practically the same manner as described in connection with Fig. 1, and the sheets may be secured together in the same way as described in connection with Fig. 1. The locking means employed for securing the sheets together may also be employed for locking adjacent sheets, on one side of the wall, to the flanges of the sheets, on the other side of the wall. This, however, may not be necessary under all conditions and under some conditions it may be desirable to provide separate means for locking the flanges of the sheets of one side of the wall to the sheets of the other side of the wall.

In assembling the sheets to form the wall, shown in Fig. 2, two sheets are secured together by forcing the flanged end of one sheet into the flanged end of the other sheet.

This forms in effect one open-ended or U-shaped member and the remainder of the wall is formed by securing sheets together in pairs to form the U-shaped members and 5 then placing them so that the unflanged edges of one pair overlap the interlocked flanges of an adjacent pair of sheets. It will be apparent that this method of procedure may be varied and that the wall may 10 be erected by securing all of the sheets forming one side of the wall to the floor and ceiling structure and then by erecting the sheets on the other side of the wall and forcing the flange of each sheet into the flange of one of 15 the sheets already erected.

In Fig. 3 I have shown a wall, which differs in some respects from the wall shown in Figs. 1 and 2. A sheet having a differently formed flange is employed in erecting 20 the wall of Fig. 3, but the sheets are each of the same size and shape. Each sheet 6 is provided along one vertical edge with an angular flange which consists of a member or leg 7, inclined at an obtuse angle to the sheet portion, and a leg or member 8, which is inclined at an acute angle to the leg 7, is 25 parallel to the sheet and is located on the same side of the member 7 as the sheet.

In assembling the sheets 6 to form a wall 30 they are located in two sets, with the sheets of each set overlapping each other in the manner described in connection with Fig. 1. The two sets are, however, so located with reference to each other that the edge formed 35 between the legs 7 and 8, of each flange, projects into the apex of the angle formed between a sheet 6 and its flange member 7. With this arrangement the flanges coöperate in pairs to form V-shaped stiffening members, the spacing of which depends upon the 40 width of the sheets and the amount the sheets are overlapped. Any suitable means may be employed for securing the separate sheets of one set together and additional 45 means may be also employed for securing the flanges of each set of sheets to the sheets of the other set.

A wall or partition embodying my invention may be cheaply and quickly erected, 50 and after it is erected it has all the essential characteristics of a fire-proof construction. As has been said the sheets may be expanded or otherwise prepared to receive plaster, which is applied after the wall is assembled.

Aside from the fact that a wall or partition 55 constructed in accordance with my invention is in itself fire-proof, it also has high heat insulating qualities, due to the air spaces located between the separate and opposing sets of sheets employed in its construction. 60 The width of the air spaces may be varied by varying the depth of the flanges of the sheets. It is also to be noted that the rigidity of the sheets may be materially increased by increasing the depth of the flanges. Another feature of my invention is that walls or partitions of any desired length may be 65 formed with sheets of uniform or standard width by merely over-lapping all of the sheets more or less, or by over-lapping the 70 end sheets greater or lesser amounts.

In accordance with the United States Patent Statutes, I have illustrated and described the three different embodiments of my invention, but I desire it to be understood that 75 various changes, modifications and substitutions may be made in the wall or partition illustrated, without departing from the spirit and scope of my invention as set forth in the appended claim.

What I claim is:

A wall structure consisting of a series of sheet metal members, each consisting of a main plate provided along one edge with a partition-forming flange which in turn is 85 provided with a foot-flange along its free edge, thereby giving to each member an approximately L-shape in horizontal section, 90 said members being adapted to receive and hold plaster and arranged in vertical position and spaced apart in two rows by said partition-forming flanges, the foot-flange of each member bearing against the inner face of the opposite member and the unflanged edge of each main plate being overlapped upon the outer face of the main plate of the next adjacent member, means being provided for fastening the members together at the points of overlap and also at the points where the foot-flanges bear 100 against the main plate.

In testimony whereof, I have hereunto subscribed my name this 4th day of October, 1912.

WILLIAM M. GOLDSMITH.
